Primary Examiner — Sandra Snapp(74) *Attorney, Agent, or Firm* — Westerman, Hattori, Daniels & Adrian, LLP(57) **CLAIM**

The ornamental design for a modular seat component, as shown and described.

DESCRIPTION

FIG. 1 is an isometric view of a modular seat component showing my new design.

FIG. 2 is a front elevational view of the modular seat component of FIG. 1.

FIG. 3 is a right side elevational view of the modular seat component of FIG. 1, the left side elevational view being a mirror image thereof.

FIG. 4 is a rear elevational view of the modular seat component of FIG. 1.

FIG. 5 is a top plan view of the modular seat component of FIG. 1; and,

FIG. 6 is a bottom plan view of the modular seat component of FIG. 1.

The broken line showing of brackets in FIGS. 1-6 is included for the purpose of illustrating use and environment and forms no part of the claimed design.

1 Claim, 1 Drawing Sheet(56)
